UNHAIRING MACHINE

John T. Kagel, Sr., Jamaica, N. Y.

Application August 16, 1946, Serial No. 691,157

4 Claims. (Cl. 69—26)

1

My invention relates to machines for preparing furs and more particularly to a machine for removing so called "dog" or "water" hair from a fur and thereby refining it.

The object of my invention is to provide a fur refining machine having a hingedly supported working table arranged under a scraper roller, so that a fur placed on the table can be treated by the scraper roller.

Another object of my invention is to provide a fur refining machine having a scraper roller equipped with a plurality of resilient fins extending spirally along the roller, and a hingedly supported working table arranged underneath the scraper roller, so that a fur placed on the table can be forced against the rotating roller.

Other objects of my invention may appear in the following specification describing my invention with reference to the accompanying drawings illustrating a preferred embodiment of my invention.

It is, however, to be understood that my invention is not to be limited or restricted to the exact construction and combination of parts described in the specification and shown in the drawings, but that such changes and modifications can be made, which fall within the scope of the claims appended hereto.

In the drawings

Figure 1 is a top view of the fur refining machine according to my invention, the guard and exhaust being indicated in broken lines.

Figure 2 is a front elevation of Figure 1, the guard being shown partly broken away, and the foot treadle being omitted.

Figure 3 is a sectional view taken on line 3—3 in Figure 2.

Figure 4 is a fragmentary top plan view of the working table, the different layers thereof being shown as broken away to show the several layers.

Figure 5 is a vertical sectional view through Figure 4, and

Figure 6 is a fragmentary side view of a scraper roller used in connection with my invention.

The fur refining machine forming the subject matter of my invention has a frame consisting of four uprights 10, which are connected with each other by four cross pieces 11 and four longitudinal side pieces 12. To stiffen this frame the four uprights 10 are fastened onto and extend upwardly from two longitudinal bottom pieces 13.

Onto the inside edges of each pair of uprights 10, located at the ends of the frame, a support member 14 is fastened extending transversely of

2

the frame, and a table top generally indicated by the index numeral 15 is pivotally mounted on the support members 14 by means of hinges 16 fastened to the front parts of the members.

5 The table top 15 is preferably made from a wooden layer 17, onto which a layer of rubber 18 is arranged. The rubber is covered by heavy canvas 19, which is fastened to the wooden layer 17. A plurality of cross members 20 extends 10 transversely of the table top and is secured to the under side thereof.

The support members 14 are arranged on the uprights 10, so that the upper surface of the table top 15 is located at the same level as the 15 top edge of the upper longitudinal side pieces 12, when the table top 15 rests on the two support members 14.

The upper portion 20' of a flat lifting bar 21 is twisted and bent at right angles to the 20 main downwardly extending portion and is securely fastened to the underside of the table top 15 adjacent the rear edge and in the longitudinal center thereof.

A forwardly extending lever 22 is pivotally connected with the lower end of the lifting bar 21 and the forward part of this lever is pivotally connected with two short uprights 23 on the bottom piece 13. The front end of this lever extends forwardly beyond the front bottom piece 13 and 30 is twisted to form a pedal 24.

A forwardly extending square frame 25 is fastened to the middle portion of the front longitudinal bottom piece 13 and supports a platform or stand 26 adjacent to the pedal 24, which 35 extends into the frame 25. Over the pedal 24 a cover 27 is hingedly connected with the front cross member of the frame 25 and extends above the pedal 24 preventing accidental movement or actuation of the same.

40 On each top cross piece 11 of the main frame a bearing carrier 28 is fastened symmetrically to the longitudinal center line of the frame.

The lower portion of each bearing carrier 28 extends downwardly along the inner side of the 45 corresponding cross piece 11 and the upper carrier portion extends over the top of said cross piece and rests thereon.

On each carrier 28 a bearing 29 is securely positioned, and the axle 30 of a scraper roller 31 50 is rotatably supported by these bearings.

A plurality of scraper fins 32, preferably seven, are arranged on the scraper roller 31 and extend lengthwise and spirally thereto.

The fins can be made from any desired and 55 suitable material, but preferably they are con-

structed from automobile tire material, consisting of $\frac{1}{4}$ " of rubber cemented on a four-ply textile base. The fins 32 are arranged on the roller 31 at equal distances from each other.

On one end the axle 30 of the scraper roller 31 extends beyond the corresponding bearing 29 and a pulley 33 is rigidly mounted on this end of the axle 30.

Underneath the pulley 33 a motor 34 is arranged on a bracket or platform 35 supported by the lower cross piece 11 of the main frame. A second pulley 36 is rigidly mounted on the shaft of the motor 34, and a belt 37 is trained over the two pulleys 33 and 36.

A guard housing 38 surrounds the upper half of the scraper roller 31 and is formed integrally with a forwardly extending air intake 39 and a rearwardly extending exhaust 40 leading to a suction fan (not shown).

The guard, air intake and exhaust are fastened to and supported by the main frame in any desired conventional manner.

When the fur refiner described above is to be used, the motor 34 is turned on, driving the scraper roller 31 in clockwise direction in Figure 3.

A fur to be treated (not shown) is placed on the table top 15 by shoving it underneath the roller. The pedal cover 27 is pivoted back to permit access to the pedal 24, which is then pressed down, pivoting the rear end of the lever 22 upwardly and thereby lifting the rear end of the table top 15 and forcing the fur thereon into contact with the rotating fins 32, which remove the objectionable "water" or "dog" hairs, leaving only the fine or "down" hair on the fur. The removed hairs are sucked through the exhaust, preventing them from molesting the operator of the fur refining machine.

Having described my invention I claim as new and desire to secure by Letters Patent:

1. A fur refining machine having a main frame including a scraper roller rotatably mounted on top of the main frame and a table top hingedly supported by the main frame underneath the scraper roller, the scraper roller being equipped with a plurality of scraper fins, and means for pivoting the table top upwardly into contact with the scraper fins, said means consisting of a lifting bar fastened to the underside of the table top, and a pedal lever pivotally connected with the lower free end of the lifting bar and pivotally supported intermediate its ends by the main frame, the forward end of the pedal lever

having the shape of a pedal, a platform formed on and extending forwardly from the bottom of the main frame, a platform frame surrounding the pedal and a cover hingedly connected with the platform frame and adapted to be arranged over the pedal and cover the same.

2. A fur refining machine having a main frame including a scraper roller rotatably mounted on top of the main frame and a table top hingedly supported by the main frame underneath the scraper roller, and consisting of a wooden base, a layer of rubber on said wooden base and a heavy textile cover protecting the layer of rubber and fastened to the wooden base.

3. A fur-refining apparatus of the class described comprising, a main frame, a scraper roller rotatably mounted on the upper side of said main frame, a table top hingedly supported by said main frame beneath said roller, a lifting bar having its upper end secured to said table top, a pedal lever pivotally associated with the lower end portion of said lifting bar and extending outwardly from the bottom of the forward side of said main frame, a platform member extending outwardly from the bottom of the said forward side of said main frame disposed closely adjacent said pedal lever, an auxiliary frame member surrounding both said lever and platform member, and a cover hinged to said auxiliary frame member for swinging positions between positions exposing said pedal lever and covering the same.

4. A fur-refining machine of the class described comprising, a main frame, a scraper roller rotatably mounted on the upper side of said main frame, and a table top member hingedly supported by said main frame beneath said roller, said table top member consisting of a relatively rigid base portion provided with a layer of relatively resilient material thereon and a protective textile covering overlying said layer and secured to said base portion.
